The ornamental design for the computer carrier, as shown and described.

DESCRIPTION

FIG. 1 is front prospective view of the computer carrier.

FIG. 2 is a front elevational view of the computer carrier.

FIG. 3 is a right side elevational view of the computer carrier.

FIG. 4 is a left side elevational view of the computer carrier.

FIG. 5 is a prospective back view of the computer carrier.

FIG. 6 is a top plan view of the computer carrier; and,

FIG. 7 is a bottom plan view of the computer carrier.

The cross-hatching represents a material or pattern that is understood to cover the entirety of the area on which it is shown. The broken lines shown are understood to represent stitching.
